TO CAMEL COMPANY, OF CHICAGO, ILLINOIS, A CORPORATION OF ILLINOIS

WEATHERING MEANS FOR HOUSE CAR END DOORS

Application filed May 25, 1929. Serial No. 365,810.

This invention relates to improvements in weathering means for house car end doors.

In the customary construction of house cars a substantially wide door opening is provided at the ends. The corner posts are secured to the top end plate forming the door frame. The doors generally comprise a pair of door members which are hinged to the corner posts and swing outwardly. Because of the large size of the doors, the difficulty of obtaining exact dimensions and due to the expansion and contraction which may occur, it is not practicable to have a tight fit between the door members and the door frame. The doors customarily seat on the inner sides against a flange of the door frame but a small space will remain between the upward ends of the door and the frame. This space permits the entrance of rain and cinders into the interior of the car unless weathering devices are used.

It has been proposed to use a deflecting strip secured to the end plate to baffle the elements. It is obvious that the deflecting strip cannot extend below the upper edge of the doors and therefore the wind may swirl the rain beneath the deflecting strip. Additional complications arise in providing weather means due to the presence of the upper lock casting which engages with the locking bar for the door which requires that the weathering strips be so designed that they will not interfere with the operation of the locking means.

Further, it is customary to form the upper corners of the doors at the hinged sides with a curvature from the upper edges to the side edges. The weathering means must therefore be so designed that it will extend around the curved corners down to the points at which the vertical sides of the doors begin.

It has been proposed to use a door sheet on the outside of the doors which extends above the upper ends of the doors and contacts with the end plate, but this arrangement is not desirable since any moisture that gets on the inside of the door sheet is liable to set up corrosion.

It is, therefore, an object of the present invention to provide improved weathering

means for house car end doors which may be readily formed and secured to present designs of doors without the necessity of being coped to allow for the lock casting.

It is further an object of the present invention to form the weathering means for each door from a continuous fabricated strip that may be secured to the upper edge of the door and extend around the curved corner. 55

It is further an object of the present invention to form the weathering strips that moisture which does pass behind the weathering strip will not be collected in the space at the upper edge of the door but will be allowed to pass outside of the door before any 60 corrosion is set up. 65

A particular feature of the present invention consists in the formation of a weathering strip including an upwardly extending flange which is adapted to contact with the end plate and a downwardly extending flange that is arranged to be secured to the door and in which the downwardly extending flange is formed with a plurality of depressions forming passages communicating from behind the weathering strips to the outside of the doors. 70 75

Further objects and advantages of the present improvements will be more readily apparent from the following description taken in connection with the attached drawings in which— 80

Figure 1 is a fragmentary elevational view of a house car end provided with doors having the present improvements applied thereto. 85

Figure 2 is a sectional view taken on the plane indicated by 2—2 in Figure 1.

Figure 3 is a similar view taken on a plane indicated by 3—3 in Figure 1.

Figure 4 is an additional sectional view taken on the plane indicated by 4—4 in Figure 1. 90

Figure 5 is a detail section through a portion of the weather strip in the plane indicated by 5—5 in Figure 1. 95

Figure 6 is a fragmentary elevation illustrating a modified construction.

Figure 7 is a sectional elevation on the plane indicated by 7—7 in Figure 6.

In the drawings there is shown the cus- 100

tomary construction of a house car end including corner posts 10—10 secured at their upper ends to the end plate 11 which is provided with a central lock casing 12. Upper 5 hinges 13—13 are shown secured to the corner posts and to the door members 14—14. The pair of door members 14—14 cooperate to close the end opening of the house car and may be locked in place by a customary locking bar 15. According to the customary construction, the door casing may be formed by a Z-bar 16, which is shown in the sectional views in Figures 2, 3 and 4, as having its upwardly extending flange 17 secured to the 10 lower edge of the inner side of the end plate 11 by the rivets 18. It should be noted that the doors are formed with curved upper corners 19—19. The top frame of each of the doors 14—14 comprises a channel member 20, 15 the upper surface of which is slightly downwardly and outwardly inclined, as shown in the sectional views in Figures 2, 3 and 4. The rear depending flange of the door frame 20 is arranged to contact with the depending 20 flange 21 of the Z-bar 16.

As previously stated, it is not desirable to provide a tight fit between the doors 14—14 and the door receiving casing. Therefore in Figures 2, 3 and 4 there is shown a space 22 25 between the Z-bar 16 and the door frame 20. This space 22, if not closed by some form of sealing means, will permit the rain to be driven in and pass behind the door to the interior of the car and thus cause damage to 30 the contents. Therefore, in the present improvements a weather strip 23 is provided which is secured to the door and arranged to overlap the end plate 11 when the doors are in closed position.

40 In the sectional Figures 2, 3 and 4 the lower depending flange 24 of the weather strip is shown as fastened to the upper edge of the door by the rivets 25. The upwardly extending flange 26 of the weather strip is slightly 45 inwardly swedged, as shown in Figure 3, and, when the doors are in closed position, the flange 26 will be pressed into contact with the end plate 11. It is obvious that such an arrangement will prevent any material portion 50 of the rain or cinders from being driven within the space 22 but if such leakage does occur, it is not desirable that the moisture collect in the space 22. If the moisture should collect within the space 22, corrosion is liable 55 to be set up between the weather strip and the door frame.

An important feature of the present invention therefore resides in the formation of the depending flange 24 of the weather strip with 60 a plurality of transversely extending depressions 27. The depressions 27 are formed in such a manner that they provide passageways from the chamber 22 downwardly to the outside of the doors, as will be evident in Figures 2 and 3. The depressions or indentations 70

27 are so formed that they stop just above the upper edge of the door frame 20 so that a continuous surface contact is maintained between the upwardly extending flange 26 and the end plate, therefore light is not 75 reflected inwardly of the car.

From Figures 3 and 4 it will be noted that the flange 26 may extend just beneath the lock casing 12 without necessitating any change in its contour. It is desirable that a plurality of the indentations 27 be provided, and, in Figure 1, we show a suitable arrangement. It should further be noted in Figure 1 that the weather strip 23 which is secured to one door is formed in two pieces, one portion being that along a substantially horizontal portion of the door and the other comprising the curved corner. It will, however, be evident that, if desirable, the parts may be formed in one integral strip without departing 80 from the principles of the invention.

As illustrative of a modified form of weather strip in which discharge is permitted from the space 22 between the door 14 and the door casing formed by the Z-bar 16, we 85

show, in Figures 6 and 7, a construction in which there is provided a weather strip 30. The lower flange 31 of the weather strip 30 is secured to the door 14 by the rivets 32. In this form, instead of providing depressions 90 or indentations in the lower flange of the weather strip, spacing members 33 are inserted and are secured by each pair of rivets 32.

Intermediate the spacing members 33 will be formed passages or spaces 34 between 95 the weather strip 30 and the door frame 20 which will permit the discharge of moisture collected in the space 22. The upper flange of the weather strip 30 is inwardly swedged, as at 35, and includes an upper flange 36 100 which will closely contact the lower edge of the end plate 11 when the door is in closed position. This flange 36 will be in continuous contact with the end plate, while portions of the lower flange 31 will be separated from the door at the spaces 34. It will be apparent 105 that such a structure is relatively easier to manufacture than the formation disclosed in Figures 1 to 4, inclusive.

Various changes and modifications may be 110 made in the particular embodiment of the present improvements without departing from the spirit of the invention as expressed in the appended claims.

We claim:

1. In house car end construction, a door 115 casing comprising an end plate and corner posts, doors hinged to said corner posts, weather strips secured to the upper edges of said doors, said strips being arranged to overlap and contact with said end plate when said doors are in closed position and means permitting passage of moisture collected behind 120 said weather strips outside of said door.

2. In house car end construction, a door 125

- casing including corner posts, an end plate, doors hinged to said corner posts, weather strips secured to the upper edges of said doors, said weather strips being arranged to overlap and contact with the lower edge of said end plate when said doors are in closed position, said weather strips and said door being formed to provide a plurality of open passageways between the back side of said weather strip and the outer side of said door. 5
3. In house car end construction, a door casing including corner posts and an end plate, doors hinged to said corner posts, weather strips secured to the upper edges of said doors, said weather strip comprising an upwardly extending flange arranged to overlap and continuously contact the lower edge of said end plate when said doors are in closed position and a downwardly depending flange 10 adapted to be secured to said doors, said downwardly depending flange including a plurality of indentations formed to provide substantially vertical passageways between the upward end of said doors behind said weather strip and the outer side thereof. 25
4. In a device of the class described, a door casing, a door hinged to said door casing, a weather strip secured to the upper edge of said door, said weather strip having an upwardly extending flange arranged to overlap and continuously contact with said door casing when said door is in closed position, said door and said weather strip forming downwardly extending passageways arranged to 30 permit the discharge of matter collected behind said weather strips. 35
5. In house car end construction comprising a door casing including corner posts, an end plate secured to the upper end of said corner posts, a door hinged to one side of said door casing, said door casing and said door cooperating to form a curved corner between the hinged side and the upper edge of said door, a weather strip secured to the upper edge of said door extending around said curved corner to a point at which the vertical side begins, said weather strip including an outwardly directed flange arranged to overlap and contact with said door casing when said door is in closed position and said weather strip being provided with a plurality of depressions starting at points beneath said contacting flange and extending to the lower edge of said weather strip. 45
6. In house car end construction, a door casing, a door hinged to one side of said door casing, weathering means at the top of said door, said means comprising a weather strip secured to the upper edge of said door, said strip having alternating portions which are spaced from said door, said spaced portions forming passages extending downwardly from the outer edge of said door to the lower edge of said weather strip, said strip having an upwardly extending flange arranged to 50
- overlap and continuously contact with said door casing when said door is in closed position. 55
7. In house car end construction, a door casing including an end plate, corner posts secured to said end plate and a Z-bar member secured to the inner side of said end plate to form a door-receiving opening, a door hinged to one of said corner posts, a weather strip comprising continuous upper and lower flanges, each of said flanges extending in one plane, means for securing the lower flange of said strip to said door, spacing members inserted between the lower flange of said weather strip and said door, said spacing members being relatively spaced to form passage therebetween leading downwardly from the outer edge of said door to the lower edge of said weather strip, the upper flange of said weather strip being arranged to overlap and continuously contact with the lower edge of said end plate when said door is in closed position. 70
8. In a door construction, a door casing, a door arranged to fit into said door casing, weathering means carried by the door arranged to overlap the door casing at the upper edge of the door and means permitting escape of fluid collected behind said weathering means outside of said door. 80
9. In a door construction, a door casing including an inwardly extending flange in a plane rearwardly spaced from the front plane of said door casing, a door arranged to fit into said door casing and seat against said flange when in closed position, weathering means carried by the door arranged to overlap the front plane of the door casing at the upper edge of the door and means permitting escape of fluid collected behind said weathering means outside of said door without passing inside of said door past said flange. 90
